US00D968651S

(12) United States Design Patent (10) Patent No.: US D968,651 S
(45) Date of Patent: * Nov. 1, 2022

(54) BUILDING

(71) Applicant: MSG Entertainment Group, LLC,
New York, NY (US)

(72) Inventors: James Lawrence Dolan, Oyster Bay, NY (US); David Ernest Dibble, San Francisco, CA (US)

(73) Assignee: MSG Entertainment Group, LLC,
New York, NY (US)

() Term: 15 Years

(21) Appl. No.: 29/800,508

(22) Filed: Jul. 21, 2021

(51) LOC (13) Cl. 25-03

(52) U.S. Cl.

USPC D25/19

(58) Field of Classification Search

USPC D25/1, 7, 13, 18, 19, 31, 33

CPC E04B 1/166; E04B 1/3205; E04B 1/3211;
E04B 1/346

See application file for complete search history.

(57) CLAIM

The ornamental design for a building, as shown and described.

DESCRIPTION

FIG. 1 is a top perspective view of a building showing the claimed design;

FIG. 2 is a rear view thereof;

FIG. 3 is a front view thereof;

FIG. 4 is a right side view thereof;

FIG. 5 is a left side view thereof; and,

FIG. 6 is a top view thereof.

The broken lines in the figures show portions of the building or video content thereof that form no part of the claimed design.

The dot-dash broken lines in the figures show boundaries that form no part of the claimed design.

1 Claim, 6 Drawing Sheets
